CLAIM

The ornamental design for a tool for a power hammer, substantially as shown and described.

DESCRIPTION

FIG. 1 is a front elevational view of the tool for a power hammer showing our new design;

FIG. 2 is a rear elevational view thereof;

FIG. 3 is a right side elevational view thereof, the left side being a mirror image;

FIG. 4 is a top plan view thereof;

FIG. 5 is a bottom plan view thereof;

FIG. 6 is a perspective view thereof shown at a reduced scale;

FIG. 7 is a perspective view of a tool for a power hammer showing an alternate embodiment of our new design;

FIG. 8 is a bottom plan view thereof;

FIG. 9 is a right side elevational view thereof, the left side being identical to that shown in FIG. 6; and

FIG. 10 is a top plan view thereof.

The shank portion of the tool in FIGS. 1, 2, 3 and 9 is shown broken away for convenience of illustration only.

The left side elevational view of the tool of FIG. 7 is identical to the left side elevational view of the tool of FIG. 6.

FIG. 1

FIG. 2

FIG. 3

FIG. 4

FIG. 5
